REMOVABLE CONTROL PLATE FOR
ACCOUNTING MACHINES

Walter A. Anderson, Bridgeport, Conn., assignor
to Underwood Corporation, New York, N. Y., a
corporation of Delaware

Application June 23, 1951, Serial No. 233,234

1 Claim. (Cl. 235—60.5)

1

This invention relates to accounting machines having a traveling paper carriage, and more particularly to removable control plates therefor.

In accounting machines such as described above, a plurality of machine function controlling elements are provided, said elements being variously actuated, in successive columnar positions, by means of pins fixed on a control plate supported in the traveling carriage.

Many users of accounting machines utilize the machine for different types of work, and it is, therefore, frequently desirable to substitute for a plate carrying pins positioned thereon to actuate the machine function controlling elements for performing one type of work, another control plate set up to produce work of another character.

It is, then, an object of the present invention to provide an improved means for attaching a machine function control plate to a traveling carriage whereby the plate is quickly and readily attachable and detachable, and which means will position the control plate and the pins carried thereby in correct relation with the machine function controlling elements.

Another object of the present invention is to provide a removable control plate and improved attaching means therefor that are both rigid and simple in construction, economical to manufacture and assemble in the machine, and accurate and dependable in operation.

With these and incidental objects in view, the invention consists in certain novel features of construction and combinations of parts, the important elements of which are set forth in appended claims, and a preferred embodiment of which is hereinafter described with reference to the drawings which accompany and form part of the specification.

In the drawings:

Figure 1 is a top plan view showing the control plate attached to the carriage, and resting in normal position.

Figure 2 is a partial side view in vertical elevation, of an accounting machine embodying the present invention, taken along the line 2—2 of Figure 1.

Figure 3 is an enlarged sectional view taken from the line 3—3, Figure 1, showing the means provided for locking the control plate in operating position, and

Figure 4 is a front view of the left hand mounting means for the control plate.

The invention is herein exemplified in a machine similar in character to that disclosed in

5 Patents Nos. 1,946,505 and 1,946,823, to O. J. Sundstrand, dated February 13, 1934, to which reference may be made for an understanding of features of construction and mode of operation not fully described or illustrated herein.

The present disclosure is an improvement on the mechanism shown in my Patent No. 2,020,282, issued November 12, 1935.

Referring to Figure 2, the machine includes a 10 traveling paper carriage indicated generally at 10. The carriage includes side plates 11 and 12, Figure 1, supported in spaced relation on a frame member 13, Figure 2, said frame member 13 being supported for lateral movement on anti-friction members 14 carried on a rail 15 mounted on machine frame 17. Also supported on the machine frame 17, by means not shown, is a bracket 18 carrying machine function controlling slides 20. Supported in the end walls 11 and 12 15 of carriage 10 is a control plate 21 in which is fixed pins 23 for engagement with the machine function controlling slides 20 during tabulation of the carriage 10 and for retaining the slides 20 in actuated position while carriage 10 is positioned in a columnar position. The rear edge of the control plate 21 is supported during the lateral movement of the carriage by a roller 24 mounted on the frame 18, to position the pins 23 vertically with relation to the control slides 20. 20 The plate 21 is pivoted in the carriage 10, and is rocked clockwise, Figure 2, in a manner similar to that described in Patent No. 1,946,505 above referred to, to release the plate 21 and the carriage from arrest by one of the controls 20 for tabulation during a working lateral movement, and to keep pins 23 clear of the control slides 20 25 during return movements of the carriage.

While control plate 21 is pivotally supported in the carriage and must have considerable resistance to endwise movement, yet the plate is readily attachable and detachable. To this end, the plate 21 is firmly secured to a bar 26, by any suitable means, as for example screws 27, Figure 1. One end of bar 26 carries a member 29, Figures 1 and 4, secured therein having a conically shaped portion 30 in which is fixed a pin 32. Pivoted in the left side carriage plate 12 and in a bracket 33 fixed thereon is a member 35 having a slotted recess 36 for slidably receiving the conically shaped portion 30 and pin 32 of member 29. Fixed in the other end of bar 26 is a stud 39 having an annular groove 41, and a tapered end portion 42. Fixed on a bracket 44 secured to the right side carriage plate 11 is a sleeve 47 having an axially extending hole 48 for receiving

member 39. Sleeve 47 is partially cut away on the left side to provide an open sided shelf for supporting shaft 26 when the control plate 21 is being attached to the carriage.

To attach the control plate, see Figure 1, the carriage is first positioned to its rightmost position to eliminate interference from the control slides 20. In this position the conical portion 30 of the plate 21 is inserted into the slotted sleeve 35 and is moved leftwardly until tapered end 42 of stud 39 is clear of the bottom of the cut away portion of sleeve 47. The right hand end of bar 26 is now moved forwardly onto the shelf of sleeve 47 and in this position is moved rightwardly, with stud 39 entering hole 46 in sleeve 47 until the right end of bar 26 abuts the left side of the uncut portion of sleeve 47 to position pins 23 in the control plate 21 in the correct position relatively to control slides 20.

When the control plate 21 is moved to such right hand position, it is secured therein, to prevent its becoming loose during operation of the machine. For such securing of plate 21, a locking member 53, see Figure 3, is supported in a slot 54 and pivoted on a pin 56 in sleeve 47. Referring to Figures 1 and 3, locking member 53 is provided with an arcuate portion 57 for engagement in the annular groove 41 in member 39, under the tension of a spring 59, to prevent lateral movement of the control plate 21.

To enable manual release of the control plate 21, locking member 53 is provided with an ear 60 extending outwardly below the carriage side plate 11 which ear 60, when depressed, rocks the locking member 53 about pin 56 and lifts the arcuate portion 57 thereof from engagement in the annular groove 41 in stud 39. The control plate is then readily moved leftwardly as viewed in Figure 1, until stud 39 is clear of the bottom of the cut away portion of sleeve 47, is then swung rearwardly from sleeve 47, and the control plate is drawn rightwardly to withdraw cone 30 and pin 32 from slotted recess 36 of sleeve 35 and so enable complete removal of control plate 21 from the machine.

During operation of the machine, the rocking of the control plate 21 for tabulating as above set out and in the manner disclosed in the patent referred to gives rise to some noise. To prevent such noise, the plate's movement is controlled during its restoring movement. For this purpose, a

lever 62, Figure 1, is fixed on sleeve 35 and is connected by means of pin and slot connection 63 with a cradle 65 pivoted on a stud 66 fast in the carriage side plate 12. Cradle 65 has firmly fixed therein a pin 68 which is connected to a dash pot 69 on carriage side plate 12. The dash pot 69, in the usual manner, enables free and easy raising of the control plate 21, but retards and cushions the restoring movement of the plate to provide quiet operation.

The above description is of a preferred embodiment of my invention but is not to be taken in a limiting sense as many variations are possible all coming within the scope of the following claim.

What is claimed is:

In a machine of the class described having a frame, function control elements thereon, and a traveling carriage, the combination of a control plate, members thereon to contact said function control elements in different positions of said carriage on said frame, and releasable means for pivotally mounting said control plate in said carriage for movement about an axis parallel to the direction of movement of said carriage, said releasable means comprising a bar to which said control plate is secured, a round tapered portion at each end of said bar the axis of each portion being parallel to the axis of said bar and one of said tapered portions having a cylindrical groove therein, recessed sleeves on the carriage to receive said tapered portions, the space between said sleeves being less than the length of said bar and said portions, one of said sleeves being recessed to at least a depth equal to the difference between said length and said space, and latching means on the other sleeve engageable with said groove when said tapered portion is inserted in the recess of said sleeve to hold said bar and said control plate in a fixed lateral position.
